[57] **ABSTRACT**

A method of stressing and anchoring the wires of a bundle or bunch of tensioning wires or the like for a concrete structure by means of clamping wedges and an anchoring body, which comprises the steps of loosely placing an anchoring head equipped with wire receiving bores onto the wires while the wires are in untensioned condition. Clamping wedges are inserted into the wire receiving bores and are fixedly retained therein without the wedges clamping the wires. The anchoring head together with the thus inserted wedges is displaced along the wires into a recess of the concrete structure accommodating the ends of the wire bunch, displacement occurring through a distance approximately corresponding to the length of elongation of the wires which is contemplated. Then in this position of the anchoring head the clamping wedges are pressed against the untensioned wires into a wire clamping position, the wire bunch is tensioned, tensioning or stressing occurring during withdrawal of the anchoring head from the concrete structure recess, whereupon the withdrawn anchoring head is supported against the concrete structure.

METHOD FOR STRESSING AND ANCHORING WIRES OF A BUNDLE OF TENSION WIRES

BACKGROUND OF THE INVENTION

The present invention relates to a new and improved method for stressing and anchoring the wires of a bundle or bunch of tensioning wires of a concrete structure by means of clamping wedges and anchoring body.

The prior art is already familiar with a number of different proposals for stressing and anchoring of tensioning cables consisting of a number of wires or strands, by means of clamping wedges and anchoring bodies. In most of these state-of-the-art proposals the wires or strands are stressed individually or in bunches through bores in a stationary anchoring body or head through the action of the tensioning device, and thereafter are anchored by wedges.

This technique which is nowadays conventional possesses a series of drawbacks, of which the most important ones will be considered briefly hereinafter:

The wires or strands of the bundle which is to be stressed or tensioned are nested together or forced together within a sleeve along the entire length of the concrete structure. However, at the ends of the bundle the individual wires of such bundle must be spread apart owing to the required spacing between the individual bores of the anchoring head fixedly arranged at the end of the concrete structure, these bores serving to receive the clamping wedges. This spreading of the individual wires of the bundle is required to allow such wires or strands, during the tensioning or stressing thereof, to be pressed in the direction of the bundle axis against the walls of the bores. It should be evident that it is difficult to insert the clamping wedges with sufficient care into the conical bores, not only because the wires or strands are arranged eccentrically within the bores, but also because they are tightly stressed or tensioned. It is practically impossible to cleanly insert the wires without forcing them, even if each wedge set for each wire or strand is hydraulically inserted or pressed-in. This is apart from the fact that such individual insertion or pressing-in operations for the sets of wedges, at best, is only possible in practice when stressing individual wires or strands. Thus the danger exists that the individual wires or strands will be damaged by the teeth of the wedges and furthermore will not be properly anchored, so that during lowering of the tensioning device individual ones of these wires or strands will slide, something which is difficult to control.

Further, in connection with the above it might be indicated that proposals have been made for reducing the eccentricity of the wires or strands in the bores which contemplates extending the conical portion of each bore hole in which the wedges come to rest in a direction towards the center of the bundle by means of a cylindrical bore which is as narrow as possible. However, it must be indicated that this cylindrical portion of the bore cannot be so narrow that the wire or the strand is correctly centrally guided, since the introduction, especially of a number of strands and the displacement of the anchoring head along the strands in its fixed position at the end of the concrete structure must be able to be carried out with the least possible friction. There is still however a further reason which opposes narrowing of the bore holes, namely: during cutting of the wires or strands there appear threads or the like at the ends

which protrude and render more difficult the threading-in or insertion into the bores of the anchoring head. It is also for this reason that a relatively larger diameter of the bores must be provided, so that, as stated above, a faultless centering of a wire or strand is no longer ensured for.

SUMMARY OF THE INVENTION

10 Therefore, there is still present a real need in the art for a technique of stressing and anchoring the wires or strands of a wire bunch which is not associated with the aforementioned drawbacks of the prior art proposals. Hence, a primary object of the present invention is the provision of a method for stressing and anchoring the wires or the like of a bunch of wires which is not associated with the aforementioned drawbacks of the prior art and which effectively and reliably fulfills the existing need in the art.

15 20 Now, in order to implement the above objects of the invention, as well as others which will become more readily apparent as the description proceeds, the method aspects of this invention contemplate loosely placing upon the untensioned tensioning wires of the bunch an anchoring head provided with bores for receiving the wires, inserting wedges and retaining such wedges at the bores of the anchoring head which form the wedge seating surfaces without clamping the wires.

25 30 Then the anchoring head together with the wedges which have been inserted in this manner are displaced back in the recess of the concrete structure receiving the wire ends along the wires through a distance approximately corresponding to the contemplated length of elongation of the wires, and in this position of the anchoring head the wedges are pressed against the still untensioned wires into a clamping position, then the wire bunch or bundle is tensioned, so that the anchoring head which is now fixedly clamped at the wires is pulled out of the recess and supported at the end of the concrete structure.

BRIEF DESCRIPTION OF THE DRAWINGS

45 The invention will be better understood and objects other than those set forth above, will become apparent when consideration is given to the following detailed description thereof. Such description makes reference to the annexed drawings wherein:

50 FIGS. 1a, 1b, 1c and 1d, illustrate the different phases of the inventive method in accordance with the invention in conjunction with purely schematic sections taken through an anchoring location of a bunch of tensioning wires at the end of a concrete structure; and

55 FIG. 2 is a sectional view through a finished anchoring location.

DETAILED DESCRIPTION OF THE PREFERRED EMBODIMENTS

60 Describing now the drawings, in FIG. 1 there is schematically illustrated the most important procedural steps performed in the practice of the method aspects of this invention during stressing and anchoring the wires of a bunch or bundle of tensioning wires at a concrete structure by means of clamping wedges and anchoring body.

It may be assumed that the tensioning wire bundle 1 consists of, for instance, twelve individual wires or strands. This wire bundle 1 is guided in the usual manner within a tubular sleeve 3 through the concrete structure 2. Now for the purpose of anchoring these wires of the tensioning wire bundle 1 the individual wires thereof, wherein for convenience in illustration there has only been shown two of them designated at reference characters 1a and 1b, must be spread apart. This spreading apart of the individual wires or strands occurs within a cylindrical tube 4 arranged within an appropriately configured recess or opening, which has not been particularly referenced, of the concrete structure 2, and which cylindrical tube 4 is connected via a cone 5 with the tubular sleeve 3.

Now for the purpose of stressing and anchoring the wires 1a, 1b which, as shown, extend somewhat past the end face of the concrete structure 2, initially an anchoring head 6, equipped with the receiving bores or apertures 7 for the wires, is pushed onto these wires over the ends thereof. While the anchoring head 6 is still located outside of the region of the substantially cylindrical tube 4 the wedges 8, 8', provided for each of the wires 1a, 1b and so forth, are inserted into the conically widening portion of the associated bores 7. A wedge retaining or holder plate 9, which is similarly provided with the same number of holes as there are bores 7 at the anchoring head 6, is then temporarily placed at such distance over the wedge heads at the anchoring head 6 that the individual wedge members 8, 8', for instance three such wedge members being provided for each wire, are retained in the bores 7 of the anchoring head 6 and which bores 7 provide wedge seating surfaces, in such a manner that the wedges themselves do not yet fixedly clamp against the individual associated wires or strands. This has been particularly well shown in FIG. 1a.

Then the anchoring head 6 together with the loosely inserted wedges 8, 8' and also together with the thus mounted wedge retaining plate 9 are displaced back along the wires 1a, 1b into the tube or conduit 4 to assume the position illustrated in FIG. 1b, this displacement being equal approximately to the contemplated elongation length of the wires. The transition location between the tube 4 and the cone 5 can thus, for instance, advantageously serve as fixed stop means. In this position of the anchoring head 6 the wedges 8, 8' are placed into their wire clamping position by pressing the wedge retaining plate 9 against the anchoring head 6. The wedge retaining plate 9 then serves to hold these wedges 8, 8' in their wire clamping position. The pressing or contacting of the wedge retaining plate 9 against the anchoring head 6 can be undertaken from the outside, for instance by tightening screws 10 or equivalent expedients, for instance for such screws being provided for each plate. Now a wire tensioning head or wire stressing head 11 can be secured to the ends of the wires 1a and 1b. This tensioning head 11 can be constructed, for instance, similar or identical to the actual anchoring head 6, and the attachment of such tensioning head to the wires can likewise be undertaken by wedges 12, 12' and the wedge retaining or holder plate 13. A tensioning device 14 is then secured to the tensioning head 11, for instance by threading the tensioning device 14 onto external threading 15 of the

tensioning head 11. Thereafter the actual stressing or tensioning operation for the wires is performed so that these wires elongate over the contemplated length, and by virtue of which the anchoring head 6 fixedly clamped to the wires is again withdrawn out of the tube 4 into the position depicted in FIG. 1c.

In this position the anchoring head 6 is now supported at the end of the concrete structure 2, which for instance can be achieved by means of two semi-ring-shaped support plates 16 and 17. Instead of using these support plates it would also be possible to use a non-illustrated nut member which previously has been mounted and which engages with the anchoring head via an external threading provided at the anchoring head.

Now the tensioning device 14 can be lowered and removed. The protruding wire ends are then cut and the entire wire bundle or bunch, as best shown by referring to FIG. 1d, is then fixedly and securely anchored at the end region of the concrete structure 2 through the use of the wedges and the anchoring head. The wedge retaining plate 9 can be, of course, also removed and again used.

The anchoring arrangement shown in FIG. 1d and in FIG. 2 on an enlarged scale is simple to produce and, in contrast to previously fabricated anchor arrangements considerably safer, and this is especially so because the wedges 8, 8' prior to stressing or tensioning of the individual wires could be placed into their clamping position.

As already indicated above, FIG. 2 illustrates on an enlarged scale the finished anchoring arrangement for the wires as depicted in FIG. 1d. By referring to this Figure it will be recognized that the effective face of the wedge retaining plate 9 is covered with a rubber plate 18 capable of accommodating possible irregularities appearing on account of the size of the wedges, the wire diameter, and so forth.

While there is shown and described present preferred embodiments of the invention, it is to be distinctly understood that the invention is not limited thereto but may be otherwise variously embodied and practiced with the scope of the following claims. Accordingly,

What is claimed is:

1. A method of stressing and anchoring the wires of a bunch of tensioning wires or the like for a concrete structure by means of clamping wedges and anchoring body, comprising the steps of:

- a. loosely placing an anchoring head equipped with wire receiving bores onto the wires while in untensioned condition;
- b. inserting clamping wedges into the wire receiving bores and fixedly retaining such inserted wedges in said receiving bores without the wedges clamping the wires;
- c. displacing the anchoring head together with the thus inserted wedges along the wires into a recess of the concrete structure accommodating the ends of the wire bunch through a distance approximately corresponding to the contemplated elongation of the wires;
- d. then in this position of the anchoring head pressing the wedges against the still untensioned wires into a wire clamping position;

- e. tensioning the wire bunch, while withdrawing from the recess of the concrete structure the anchoring head fixedly clamped to the wires; and
- f. supporting the thus withdrawn anchoring head against the concrete structure.

2. The method as defined in claim 1, including the step of fixedly retaining the inserted wedges against wedge seating surfaces of the wire receiving bores.

3. The method as defined in claim 1, further including the step of utilizing mechanical holding means associated with the anchoring head and operable from externally of the concrete structure for fixedly retaining the wedges in a loose arrangement in the wire receiving bores and for pressing the wedges into their wire clamping position.

4. The method as defined in claim 1, wherein the anchoring head together with the therein loosely inserted wedges is displaced into the recess of the concrete structure along the wires until impacting against a stop within such recess, so as to then bring the wedges into their wire clamping position.

5. The method as defined in claim 1, including the step of using a support element engaging with the anchoring head to support such anchoring head against

the end of the concrete structure.

6. The method as defined in claim 5, wherein there is used support plate means as such support element.

7. The method as defined in claim 5, wherein there is used nut member means as such support element.

8. The method as defined in claim 3, further including the step of using as the holding means for the wedges an elastically padded-wedge holder plate.

9. The method as defined in claim 8, including the step of temporarily placing the wedge holder plate at such a distance over the wedges at the anchoring head after insertion of the wedges that the wedges remain seated in the wire receiving bores without clamping the wires, and following displacement of the anchoring head into the concrete structure recess reducing the aforesaid distance between the wedge holder plate and the anchoring head such that the wedges are pressed into contact with the wires.

10. The method as defined in claim 3, further including the step of removing the wedge holding means for reuse thereof following step (f) where the anchoring head is supported against the concrete structure.
